GOLF PLAYER'S CLUB SELECTING DEVICE

Frederick H. Ford, Waupun, Wis.

Application May 29, 1930. Serial No. 456,958.

2 Claims. (Cl. 273—77)

My invention relates to improvements in golf players' club selecting devices.

The primary object of my invention is to provide means for enabling a golf player or dealer in golf clubs to quickly and accurately determine which of a series of golf clubs will best suit the requirements of the player due to his height, length of arms and characteristic posture.

More specifically stated, my object is to provide an adjustable golf club to be used for testing purposes and which is made variable in length, (preferably length of shaft), and provided with an index suitably calibrated with reference to standard clubs of differing lengths, whereby, when the test club has been properly adjusted in accordance with the requirements of an individual player, the club best adapted for such player's requirements will be indicated by said index.

20 A further object is to provide means for adjusting the club head to vary the so-called "lie" in correspondence with variations in the aforesaid telescopic adjustment, whereby more accurate adjustments may be made than would be possible if the club head were tilted out of the normal position which it should occupy when the shank is at the proper angle of inclination.

In the drawing:

Figure 1 is an elevation of a golf club selector embodying my invention.

Figure 2 is a view of the lower end of the club as seen at right angles to Figure 1, with the toe of the club exposed in the line of vision.

Figure 3 is a fragmentary view of the telescopic portion.

Figure 4 is a view, similar to Figure 3, showing a modified means for locking the telescoping members together.

Figure 5 is a view of the lower end of a club having a wooden head and illustrating the adjustable hinged connection of the head with the shank.

Like parts are identified by the same reference characters throughout the several views.

45 Referring to Figures 1, 2 and 3, it will be observed that the grip member 10 and shaft 11 are axially adjustable. The grip member 10 may comprise a metal tube. It is preferably covered by a leather sheath 13 and may have at its upper end a cap 12, whereby the upper end portion approximates the grip portion of an ordinary club in appearance, size, and feel, and a player may hold it naturally without being influenced by impressions induced by contrast with those obtained 50 when grasping an ordinary club.

The shaft 11 has a cylindrical portion 15 which telescopes in the grip member 10 and is provided with index marks as clearly shown in Figure 3, suitably calibrated and identified with clubs of standard lengths by reference letters or characters.

The cylindrical portion 15 snugly fits within the grip member 10 and the lower end of the latter is longitudinally slotted as indicated at 16 in Figure 3, thus forming a series of resilient tongues 17 which may be clamped upon the cylindrical portion 15 by a nut 18 having at one end internal threads to engage the threaded portion 19 of the grip member 10. The interior surface of the nut 18 below the threaded portion is conically tapered, whereby upward movement of the nut on the portion 19 will compress the tongues 17 into clamping engagement with the portion 15 of the shaft.

It is thus possible to bind the member 10 to the shaft 11 with sufficient rigidity to enable a player to hold the club head in proper position, or swing it naturally into such position, readjusting its length as often as may be necessary until assured that the club is of the proper length to suit his requirements. The index will then indicate to him, his dealer, or to an instructor, the length of the golf club which he should select.

It will be obvious that a change in the length of the club, obtained by axially adjusting the member 10 upon the shaft 11, will require a corresponding change in the so-called lie or angle between a line along the sole 22 of the club and the axis of the shaft 11, in order that the sole may occupy a horizontal position when the club is naturally held by a player to whose requirements the length of the club has been adjusted. I therefore provide a hinged connection between the head of the club and the shank 23, with the axis of the pivot bolt or pin 24 perpendicular to the face 25 of the club, whereby the adjustments permitted by the hinge will not vary the pitch or oblique position of the face.

I preferably provide the lower end of the shank 23 with a fork or pair of spaced ears 26 between which the flattened extremities or inner end of the head may be received. The material composing the shank ears 26 may be slightly flexible or resilient, whereby the pivot bolt 24 may clamp them upon the flattened portion of the head when the thumb nut 27 is adjusted to clamping position. This allows the head to be frictionally held with sufficient resistance for testing purposes while allowing it to be manually readjusted by merely applying sufficient force to overcome the

friction whenever the length of the club is selected. In fact, my device constitutes a golf club, capable of being used as such, although such use will ordinarily be for testing purposes only.

Referring to the modified structure shown in Figure 4 it will be observed that the shaft 11a telescopes into the grip member 10a in the same manner as illustrated in Figure 3 but the lower end of the grip member is not slotted and is secured to the telescoping portion 15a by an ordinary set screw 28. The portion 15a of the shaft 10 will preferably be provided with an inset bearing bar or strip of metal 29 against which the inner end of the set screw impinges when in clamping position. The portion of the grip member 15 through which the set screw passes is slightly thickened to increase the threaded engagement of the screw therewith.

Referring to Figure 5, in which the club is provided with a wooden head 30, it will be observed that the hinged portion of the head is preferably 20 encased in a metal sheath 31, engageable between the ears 26b. The pivot bolt 24b passes through the flattened and jacketed portion 31 of the head to secure the head to the shank 23b in substantially the same manner that the head is 25 secured to the shank 23 in Figure 1. The shaft 11b is socketed in the shank in the same manner as indicated in Figure 1 and if desired may be secured in the socket by a screw 33.

It will be understood that the object of telescopically adjusting the shaft and grip members 30 instead of merely causing them to slide, one upon another, is to avoid distracting the player. By imitating a playing club as nearly as possible, the player is induced to grasp the selector in a 35 natural manner and the precise club suited to his needs may therefore be quickly and accurately

I claim:

1. As a new article of manufacture, a golf club selector for use in testing the requirements of an individual purchaser, comprising axially adjustable grip and shaft members indexed and calibrated for identification of clubs of standard lengths, in combination with a shank portion provided with a head connected to the shank by a pivotal joint for swinging movement about an axis parallel to the plane of the sole, the pivotal joint affording sufficient friction to temporarily maintain said head and shank in fixed relation, said head being adjustable by the hand of the operator under pressure sufficient to overcome the frictional resistance of the pivot joint to pivotal movement.

2. As a new article of manufacture, a golf club selector provided with grip and shaft members calibrated and indexed to identify clubs of standard lengths and loosely adjustable upon each other, said shaft member having a shank 100 provided with a head connected to the shank by a pivotal joint for swinging movement in a plane at right angles to the sole, the pivotal joint affording sufficient friction to temporarily maintain said head and shank in fixed relation, said head being adjustable by manual pressure sufficient to overcome the frictional resistance of the pivot joint to pivotal movement, and hand operable devices for adjusting the degree of friction of said pivotal joint.
